UNITED STATES PATENT OFFICE.

DENNIS SWEENEY, OF FARMINGDALE, NEW YORK, ASSIGNOR OF ONE-THIRD TO
MICHAEL DUNN AND ONE-THIRD TO JOHN DUNN, BOTH OF BROOKLYN, NEW YORK.

DESIGN FOR A VANITY CASE.

Application filed October 20, 1925. Serial No. 15,184. Term of patent 7 years.

To all whom it may concern:

Be it known that I, DENNIS SWEENEY, a citizen of the United States, residing at Farmingdale, in the county of Nassau and State of New York, have invented a new, original, and ornamental Design for Vanity Cases, of which the following is a specification, reference being had to the accompanying drawing, forming part thereof.

Figure 1 is a face view of the vanity case closed.

Figure 2 is a perspective view of the same opened.

I claim:

The ornamental design for a vanity case, as shown.

DENNIS SWEENEY.
